UNITED STATES PATENT OFFICE.

MARCIAL REDON, OF LIMOGES, FRANCE.

DESIGN FOR A COVERED DISH.

SPECIFICATION forming part of Design No. 22,379, dated May 2, 1893.

Application filed June 25, 1892. Serial No. 438,048. Term of patent 7 years.

To all whom it may concern:

Be it known that I, MARCIAL REDON, a citizen of France, residing at Limoges, Department of Haute-Vienne, Republic of France, have invented and produced a new and original Design for a Covered Dish, of which the following is a specification.

In the accompanying drawing, a perspective view of a covered dish embodying my design for dishes is shown.

The essential feature of my design consists of a segmental leaf shape ornamentation for the dish and cover. This ornamentation has an escalloped outer edge, beyond which a plain surface extends. The escalloped inner edge of the leaf shaped ornamentation is merged or lost in the plain interior of the surface of the dish—in the cover of the dish the segmentations of the ornamentation radiates from the center, toward the rim and at, and from, this point a series of indentations radiate toward the plain interior surface, where they are gradually lost. The sides of the dish have the same segmented leaf shaped ornamentation as the cover, with an escalloped outer edge beyond which a plain rim or edge surface extends, the inner side of this escalloped ornament being lost or merged into the plain interior surface of the ware—a series of deep indentations which are on the under side of the dish are also lost or merged into

the plain interior outer surface of same. The tray or dish into which the covered dish sets has a line of escalloped ornamentation extending around and within its plain rim on 35 its interior surface. This escalloped ornament is merged on its inner side into the plain interior surface of the dish—at intervals within the boundary of and extending into the escalloped ornamentation, an arabesque ornamentation is shown. This arabesque ornamentation is also placed at and accentuates the line of segmentation in the ornamentation in the cover and dish proper. It consists in a representation of scrolls and buds. The 40 handles are composed of a composite of the 45 scallops and arabesque as shown.

In the drawing A is the smooth interior surface. a, is the escalloped edge. a' is the deep indentations. Both a and a' merge into the 50 smooth interior A.

B, B, is the segmental line, of ornamentation.

C, C, are the handles.

d, d, is the arabesque ornamentation.

I claim—

The design for a dish substantially as herein shown and described.

M. REDON. [L. S.]
